Primary Examiner — Elizabeth A Albert*Assistant Examiner* — Karen E Eldridge Powers(74) *Attorney, Agent, or Firm* — QuickPatents, Inc.; Kevin Prince(57) **CLAIM**

What is claimed is the ornamental design for a hat, as shown and described.

DESCRIPTION

FIG. 1 is a perspective view of a hat, showing the new design; FIG. 2 is a front elevational view thereof; FIG. 3 is a rear elevational view thereof; FIG. 4 is a right-side elevational view thereof; FIG. 5 is a left-side elevational view thereof; FIG. 6 is a top plan view thereof; and, FIG. 7 is a bottom plan view thereof.

The broken lines showing a person in FIG. 1 are included for the purpose of illustrating the invention in use, and form no part of the claimed design.
